US0D1063351S

(12) **United States Design Patent** (10) **Patent No.:** **US D1,063,351 S**
(45) **Date of Patent:** **** Feb. 25, 2025**

(54) **FOOTWEAR UPPER**

(71) Applicant: **Wolverine Outdoors, Inc.**, Rockford, MI (US)

(72) Inventor: **Brenton S. Wehrmeyer**, Grand Rapids, MI (US)

(73) Assignee: **Wolverine Outdoors, Inc.**, Rockford, MI (US)

(**) Term: **15 Years**

(21) Appl. No.: **29/889,074**

(22) Filed: **Apr. 7, 2023**

(51) LOC (15) Cl. **02-04**

(52) U.S. Cl.

USPC **D2/969**; D2/923

(58) **Field of Classification Search**

USPC D2/916, 919-926, 929-946, 969-978

(57) **CLAIM**

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The figures show features in broken lines that form no part of the claimed design. The broken lines immediately adjacent the solid line portions of the design form the boundary of the design, with the broken lines forming no part of the claimed design.

1 Claim, 7 Drawing Sheets
